corporation

Application June 24, 1941, Serial No. 399,502

18 Claims. (Cl. 229—87)

This invention relates to a display container for cut flowers.

The chief object of this invention is to provide a container for cut flowers which will receive particularly long stem flowers and attractively display the same, which will protect the blossoms in shipment and prevent breakage of the stems or separation of blossoms from the stems incident to unpacking or transportation.

Another chief object of this invention is to provide a container for cut flowers which will hold the flowers in such a manner that the same, while packaged may be handled as a unit and which is of such character that the cut ends of the stems can be received by the florist's vase or water container or jar, all without wetting the container or requiring removal of the flowers from the container.

Another chief object of this invention is to provide a container for cut flowers and the like which will permit of the economical packaging of a large number of flowers in a shipping case, thereby reducing transportation costs to a minimum, as well as damage to the flowers.

This invention is particularly adapted to receive, display and protect long stem flowers, such as roses, lilies, carnations and the like, but is not necessarily restricted to these particular varieties.

The chief feature of the invention consists in the formation of a combination display container capable of accomplishing the foregoing objects, as well as being capable of fabrication from a single blank of paper board material, such as cardboard or kraft-board of like character, and which, when cut to form, can be shipped flat in bundles to the flower grower and which, to be utilized, can be easily and readily erected or set up, and which can be readily and easily filled with cut flowers, and when filled will retain same in predetermined position for transportation, display and/or storage purposes as previously set forth.

Other objects and features of the invention will be set forth more fully hereinafter.

The full nature of the invention will be understood from the accompanying drawing, the following description and claims.

In the drawing,

Fig. 1 is a perspective view of the display container for cut flowers with flowers therein.

Fig. 2 is a developed plan view of the blank required for the display container shown in Fig. 1.

Fig. 3 is an enlarged side elevational view of the upper end of the container.

Fig. 4 is a developed plan view of a modified form of upper right-hand corner of the blank.

In Fig. 1 of the drawing, B indicates the blossom portion of a cut flower having the stem S. It is usual to bundle or package twenty-five of the same as a two-dozen unit. The extra flower is included to compensate for any flower that may not be saleable when received by the retailer.

10 As illustrated in Fig. 1, these flowers are arranged in superposed groups, the uppermost and lowest group (referring to blossom and stem respectively and top and back of the unit respectively) including eleven flowers, the intermediate group including ten flowers and the lowermost and upper group containing five flowers.

Three tiers of flowers are illustrated. A lesser or greater number may be utilized, if desired or required by the number of flowers to be packaged or by the specific character of the flowers to be packaged. The distribution or number of flowers in each tier may also be varied as desired or required. The arrangement and number specifically illustrated in Fig. 1 is by way of example only.

In the drawing 10 indicates a somewhat triangular shaped body portion having the upper edge 110 and two converging side edges 11. The body portion is extended at 12. Each side edge 13 thereof is a hinge crease by which successively hinged portions 14 and 15, hinged together at 16, are connected together to form a tubular handle arrangement as shown in Fig. 1.

Each portion 15 by hinge 17 is connected to a tongue portion 18. The free ends of these tongues, when in handle formation overlap as shown in Fig. 1. Such position is maintained by the notch arrangements 19 and projections 20. Note that the notch and projection on the tongue free ends are reversed or opposed.

While the interlock can be effected with both projections exposed, the preferred interlock is as shown in Fig. 1, that is with the free ends of each tongue and the projections in concealed relation. This has the further advantage that there is no exposed portion in the handle arrangement to catch upon some object and tear the lock.

This handle envelops all flower stems so the unit can have all stems included in a vase, etc., for the purpose previously set forth. This handle also permits the unit to be picked up by and carried in one hand.

To the side edges 11 of the inverted, somewhat 55 triangular body portion 10 is secured side por-

tions 21. Projecting outwardly from each edge 22 therefrom and secured thereto by hinge creases 23 are the spaced tongues 24. These tongues are of progressively differing length because sides 11 are not parallel in the preferred form of the invention.

Each free end of the tongue includes a notch 25 and a projection 26. These tongues 24 on the same side, see Fig. 2, are substantially parallel but they do not necessarily have to be so positioned. When the sides 21 are folded upwardly and the tongues 24 are folded inwardly thelapping free ends of adjacent tongues may be interlocked. Such interlock preferably is of concealed character, as previously described, for the handle interlock and for the same reason. The connection can be reversed, however.

Herein, note the body tongue connections are alike while the handle tongue connection is just the reverse thereof. Since four tongue connections are illustrated the intermediate body tongue connections then could alternate as it were. The arrangement disclosed insures that the locking strain of the connection is not primarily on one side edge but is distributed between the edges.

As shown in Figs. 1 to 3, each upper end of the side wall 21 includes a flap extension 27 and same and the wall includes a slit 28 having angular ends 29 and the purpose of this slit extension will be set forth later.

The edge 110 is a hinge crease, directed oppositely from all prior mentioned creases, connecting intermediate head portion 111 to the body portion 10 at the top thereof. A crease 112, similar to all creases except 110, connects the remote head portion 113 to portion 111. Portion 111 then can extend rearwardly, see Fig. 3, and portion 113 forwardly forming a blossom receiving groove, and a head portion V-shape in transverse section.

Hingedly connected to each end of portion 113 by hinge crease 114 is a tongue or flap extension 115 having the notch 116 and locking projection 117. The projection 117 cooperates with the slit 28—29, as shown in Fig. 3, to maintain the head portion in angular relation to the body portion and with the groove formation as well.

Flaps 118, hinge crease connected at 119 to the opposite ends of the intermediate head portion 111 serve as stabilizers of the aforesaid formation when erected.

The method of erection and filling is substantially as follows: The head arrangement is set up by turning the sides 21 upwardly, depressing portion 111, elevating or tilting portion 113 and then securing same together as shown in Fig. 3.

Then eleven flowers are laid side by side with their stems resting on portions 10 and 12 and their blossoms seated in the groove. The upper pair of tongues is brought together and locked.

Ten flowers are then laid with their stems on portion 11 and 12 but said stems at the blossom end overlie the upper locked tongues and the blossoms lie in an upper tier relation and between flaps 27. Then the intermediate pair of tongues is brought together and locked over these stems.

The remaining five flowers are similarly positioned except that blossoms are not guarded at each end of the row. When placed, the lowermost body tongues are brought together and locked. All stems are now resting on handle portion 12. The tongues, etc., thereof are also brought together and locked and the package is complete, ready for box or carton packing

for shipment, display or for storage since the stems extend considerably beyond the bottom of the handle.

In Fig. 4 a somewhat similar form of structure is illustrated in plan. Herein numerals of the 200 series indicate parts shown in Fig. 2 and indicated therein by numerals of the primary and 100 series. It will be noted that in this form of the invention that the tongue for locking the parts in assembled relation is slightly different and the neck arrangement provides for dual locking of the tongue in the assembled position.

Other variations of the locks, etc. both in the portion illustrated in Fig. 4, as well as in the spaced cross-band arrangements shown in Fig. 1 may be effected whenever desired or required for special purposes.

While the invention has been illustrated and described in great detail in the foregoing description, the same is to be considered as illustrative and not restrictive in character.

The several modifications described herein, as well as others which will readily suggest themselves to persons skilled in this art, are all considered to be within the broad scope of the invention, reference being had to the appended claims.

The invention claimed is:

1. A display container for cut flowers including an inverted somewhat triangular shaped body portion, a blossom nesting head portion at the upper end of the body portion and extending angularly thereof in depressed relation thereto, and a plurality of spaced tongue means extending from one side of the body portion to the other and across and above the body portion.

2. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, and a tubular handle arrangement extending from the lower end of the body portion with the tubularity above the plane of the body portion for tongue means retained flower stem envelopment.

3. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, and a tubular handle arrangement extending from the lower end of the body portion with the tubularity above the plane of the body portion for tongue means retained flower stem envelopment and comprising an integral extension thereof with inwardly directed tongues having lapping free ends with an interlocking connection therebetween.

4. A display container for cut flowers including an inverted somewhat triangular shaped body portion, a blossom nesting head portion at the upper end of the body portion and extending angularly thereof in depressed relation thereto, and a plurality of spaced tongue means extending from one side of the body portion to the other and across and above the body por-

tion for the purpose described, each of said tongue means comprising a pair of tongues connected at one end to the body portion at opposite sides thereof and having lapping free ends with an interlocking connection therebetween.

5. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, and a tubular handle arrangement extending from the lower end of the body portion with the tubularity above the plane of the body portion for tongue means retained flower stem envelopment, each of said tongue means comprising a pair of tongues connected at one end to the body portion at opposite sides thereof and having lapping free ends with an interlocking connection therebetween.

6. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, and a tubular handle arrangement extending from the lower end of the body portion with the tubularity above the plane of the body portion for tongue means retained flower stem envelopment and comprising an integral extension thereof with inwardly directed tongues having lapping free ends with an interlocking connection therebetween, each of said tongue means comprising a pair of tongues connected at one end to the body portion at opposite sides thereof and having lapping free ends with an interlocking connection therebetween.

7. A display container for cut flowers including an inverted somewhat triangular shaped body portion, an angularly positioned head portion at the upper end thereof, and a plurality of spaced tongue means extending from one side of the body portion to the other for the purpose described, side flaps at each upper corner of the body portion, and flaps at each end of the angularly positioned head portion, adjacent side and end flaps being secured together.

8. A display container for cut flowers including an inverted somewhat triangular shaped body portion, a blossom nesting head portion at the upper end of the body portion and extending angularly thereof in depressed relation thereto, and a plurality of spaced tongue means extending from one side of the body portion to the other and across and above the body portion for the purpose described, side flaps at each upper corner of the body portion, and flaps at each end of the depressed head portion, adjacent side and end flaps being secured together by an interlocking connection.

9. A display container for cut flowers including an inverted somewhat triangular shaped body portion, an angularly positioned head portion at the upper end thereof, a plurality of spaced tongue means extending from one side of the body portion to the other for the purpose described, each of said tongue means comprising a pair of tongues connected at one end to the body portion at opposite sides thereof and

having lapping free ends with an interlocking connection therebetween, and a side portion substantially coextensive with each side edge of the body portion and from which extend, in spaced relation to the body portion, the adjacent spaced apart tongues.

10. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, each of said tongue means comprising a pair of tongues connected at one end to the body portion at opposite sides thereof and having lapping free ends with an interlocking connection therebetween, and a side portion substantially coextensive with each side edge of the body portion and from which extend, in spaced relation to the body portion, the adjacent spaced apart tongues, flaps at each end of the depressed head portion, the flap and adjacent upper end of the side portion having an interlocking connection to maintain the depressed position of the head portion.

11. A display container for cut flowers including an inverted somewhat triangular shaped body portion, a blossom nesting head portion at the upper end of the body portion and extending angularly thereof in depressed relation thereto, and a plurality of spaced tongue means extending from one side of the body portion to the other and across and above the body portion for the purpose described, the depressed head portion being V-shaped in section forming a blossom nesting groove.

12. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, each of said tongue means comprising a pair of tongues connected at one end to the body portion at opposite sides thereof and having lapping free ends with an interlocking connection therebetween, and a side portion substantially coextensive with each side edge of the body portion and from which extend, in spaced relation to the body portion, the adjacent spaced apart tongues, flaps at each end of the depressed head portion, the flap and adjacent upper end of the side portion having an interlocking connection to maintain the depressed position of the head portion, the depressed head portion being V-shaped in section forming a blossom nesting groove.

13. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, the depressed head portion being V-shaped in section forming a blossom nesting groove, and flaps at the ends of the head portion connected to the body portion and cooperating with the remote portion of the head portion at the ends of the remote

portion to prevent collapse of the groove formation.

14. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, side flaps at each upper corner of the body portion, flaps at each end of the depressed head portion, adjacent side and end flaps being secured together, and a tubular handle arrangement extending from the lower end of the body portion with the tubularity above the plane of the body portion for tongue means retained flower stem envelopment.

15. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, a tubular handle arrangement extending from the lower end of the body portion with the tubularity above the plane of the body portion for tongue means retained flower stem envelopment, each of said tongue means comprising a pair of tongues connected at one end to the body portion at opposite sides thereof and having lapping free ends with an interlocking connection therebetween, and a side portion substantially coextensive with each side edge of the body portion and from which extend in spaced relation to the body portion, the adjacent spaced apart tongues.

16. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, a tubular handle arrangement extending from the lower end of the body portion with the tubularity above the plane of the body portion for tongue means retained flower stem envelopment, each of said tongue means comprising a pair of tongues connected at one end to the body portion at opposite sides thereof and having lapping free ends with an interlocking connection therebetween, the an-

5 gularly positioned head portion being V-shaped in section forming a blossom nesting groove, and flaps at the ends of the head portion connected body portion and cooperating with the remote portion of the head portion at the ends of the remote portion to prevent collapse of the groove formation.

17. A display container for cut flowers including an inverted somewhat triangular shaped body portion, a blossom nesting head portion at the upper end of the body portion and extending angularly thereof in depressed relation thereto, a plurality of spaced tongue means extending from one side of the body portion to the other and across and above the body portion for the purpose described, a tubular handle arrangement extending from the lower end of the body portion with the tubularity above the plane of the body portion for tongue means retained flower stem envelopment and comprising an integral extension thereof with inwardly directed tongues having lapping free ends with an interlocking connection therebetween, each of said tongue means comprising a pair of tongues connected at one end to the body portion at opposite sides thereof and having lapping free ends with an interlocking connection therebetween, a side portion substantially coextensive with each side edge of the body portion and from which extends in spaced relation to the body portion, the adjacent spaced apart tongues, flaps at each end of the depressed head portion, the flap and adjacent upper end of the side portion having an interlocking connection to maintain the depressed position of the head portion, the depressed head portion being V-shaped in section forming a blossom nesting groove, and flaps at the ends of the intermediate head portion connected to the body position and cooperating with the remote portion of the head portion at the ends of the remote portion to prevent collapse of the groove formation.

18. A display container for a plurality of cut flowers including an inverted somewhat triangular shaped base body portion, an offset, blossom seating head at the upper end thereof, and a plurality of spaced means extending from side to side of the body portion, each successive means from the head portion except the most remote 50 means serving as a stem rest for a successive layer of flowers, and each means serving as a stem retainer, whereby all blossoms are retained in substantially flat solid panel effect for display purposes.
